[57] CLAIM

The ornamental design for an extendable lectern, substantially as shown and described.

DESCRIPTION

FIG. 1 is a front perspective view of an extendable lectern showing our new design;
FIG. 2 is a right side elevational view, the left side being a mirror image thereof;
FIG. 3 is a front elevational view thereof;
FIG. 4 is a rear elevational view thereof;
FIG. 5 is a top plan view thereof;
FIG. 6 is a bottom plan view thereof;
FIG. 7 is a rear perspective view in extended position;
FIG. 8 is a front perspective view of a modified embodiment of the extendable lectern shown in FIG. 1;
FIG. 9 is a right side elevational view, the left side being a mirror image thereof;
FIG. 10 is a front elevational view thereof;
FIG. 11 is a rear elevational view thereof;
FIG. 12 is a top plan view thereof;
FIG. 13 is a bottom plan view thereof; and
FIG. 14 is a rear perspective view in extended position.
